3 Claims

ABSTRACT OF THE DISCLOSURE

A brassiere for use during a post mastectomy convalescent period, which includes a comparatively wide torso-encircling band of an inelastic fabric at least 7 inches in width and formed with one or more pleats or folds therein. Relatively wide shoulder straps are provided and arranged so as to be capable of selective adjustment as to their length. Carried by the band is a conventional cup for reception of the healthy remaining breast and also a cup which is arranged to have a pad removably positioned therewithin at the location of the removed breast.

The present invention relates to a brassiere that is intended to be worn by a woman after a mastectomy has been performed, and is concerned primarily with the provision of a garment which may be worn by a patient immediately after the operation and during the entire post operative convalescent period with a high degree of comfort and definite assurance that she presents a normal attractive appearance.

A breast removal operation is attended by two basic factors which enter into the patient's recovery. The first is physical and the second is psychological. The two are closely interrelated and the situation may be summarized by noting that, if the patient is comfortable, has a positive confidence that she presents a normal appearance, bandages and dressings are properly accommodated and provision made for causing so called minor muscles to perform the function of primary muscles which have been stripped by the operation, her recovery is hastened and the convalescent period hastened, rehabilitation to a more normal appearance is more ensured because of more positive initial steps to this goal.

By far the larger number of mastectomies are radical operations in which a breast is completely removed and the primary muscles which had supported the breast are stripped to the shoulder. This leaves a wide area which is extremely tender and must be initially covered by dressings and bandages which are held in position by a binder. Any brassiere which covers these elements must do so without applying any localized pressure. Otherwise pressure aggravates healing, promotes infection and breakdown of incision which causes great pain to the patient. Moreover, this same degree of comfort which is achieved by the accuracy of the fit must be maintained throughout the entire convalescent period.

Besides the development of the secondary muscles which prior to the operation, had been comparatively inactive in assuming the role of maintenance of posture, difficulties incurred by surgery are also of importance. If they are not exercised they will atrophy and not be capable of supporting the adjacent shoulder in the manner necessary to attain the normal appearance. This inability of the muscles to properly support the shoulder immediately subsequent to the operation is emphasized by the patient's normal tendency to "hunch" forwardly knowing her breast has been removed. To develop the muscles weight is added to the brassiere where the breast is missing and the garment must be capable of aiding the muscles in accommodating this added weight.

During the immediate post operative period it is nec-

2

essary for the brassiere cup to contain prosthetic pads which have absorbent properties, and are replaced from time to time by fresh pads. It is to be remembered that if the recovery is to be speedy and successful it must be attended by a high degree of comfort and a peace of mind which can come only from the knowledge that the patient presents a normal appearance.

All of the conditions above outlined are accommodated by the brassiere of this invention and the desired ends attained by the structure of the brassiere which permits it to be adjusted by the patient herself to achieve an accurate comfortable fit any time during the convalescent period.

The instant brassiere is visualized as including, as an essential element, a comparatively wide torso encircling band of a non elastic fabric, being at least seven inches wide, which is susceptible of bearing one or more pleats or folds formed therein, together with relatively wide shoulder straps also of non elastic fabric which have their front ends permanently anchored to front portions of the band and being sufficient length to permit connections to the back of the band on stitching which may be removed so that the effective length of the shoulder straps may be adjusted as occasion demands.

The band aforesaid terminates in front portions the end edges of which are joined by conventional detachable connecting means such as hooks and eyes. One front portion carries a cup which receives the healthy remaining breast. The other portion carries a cup that is mounted thereon in a partially detachable manner so that a pad may be removably positioned therein.

The properties and advantages of this subject brassiere may be summarized by noting that it is of a washable, non elastic fabric; is adjustable as to girth and shoulder strap length by the patient without including buckles, clasps of similar metallic devices; is sufficiently wide at all critical areas to localize pressure there; includes a weighted, prosthetic pad having absorbent properties for pressure or possible discharge from the wound that restores a normal appearance to the patient; and may be born with a high degree of comfort during the convalescent period.

Various other more detailed objects and advantages of the invention, such as arise in connection with carrying out the above noted ideas in a practical embodiment, will in part become apparent, and in part be hereinafter stated, as the description of the invention proceeds.

For a full and more complete understanding of the invention reference may be had to the following description and accompanying drawing, wherein:

FIGURE 1 is a perspective of a brassiere designed in accordance with the precepts of this invention.

FIGURE 2 is a detailed perspective on an enlarged scale of a portion of the meeting ends of the band.

FIGURE 3 is another detailed perspective of that pattern of the brassiere which houses the removable prosthetic pad.

FIGURE 4 is a detailed perspective of the pad per se with parts broken away.

FIGURE 5 is a perspective of the garment looking from the rear prior to any adjustment thereof and

FIGURE 6 is another perspective depicting how the adjustments are effected.

The convalescent brassiere of this invention includes as an essential element a torso including A and that is referred to in its entirety by the reference character B. The band B is made of a washable, non elastic and non stretchable woven fabric and, for the purpose of this invention may be considered as comprising front portions 10 and 11, side parts 12 and 13 and a back 14. It will be understood that these parts are all integrally pieced in a one piece band that has a minimum width of seven

inches. In most cases where the patient is more obese it is wider.

The front portion 10 terminates in an end edge 15 while the front portion 11 has an end edge 16. When the garment is worn the ends of the front portions 10 and 11 are fastened together. This may be accomplished by a conventional fastening device such as the hook and eye arrangement depicted. Thus the front portion 10 carries on its outer exposed face adjacent to the edge 15 a plurality of eyes 17 while the front portion 11 is provided on its inner face with a corresponding number of hooks 18.

While in some instances a mastectomy may involve the removal of both breasts the greater number of each operations remove only a single breast. Hence, the instant brassiere is described as being so designed and purely by way of example, to accommodate the removal of a left breast.

The front portion 11 is cut away as shown at 19 and mounted over the opening formed thereby is a cup 20. The latter receives the healthy remaining breast and is of a semiforced padded construction as is well known in this field. It may be semiforced by a supporting bottom strap 21.

A partially removable cup 22 is shown as mounted on the front portion 10. The lower part of the cup 22 is securely held in position by a bottom strap 23. Substantially the lower half of the cup 22 is permanently secured to the front portion 10 by sewing along the lines 24 and 25. This leaves the upper half of the cup 22 free of the band portion 10. It may be detachably secured thereto by the complimentary elements of sway postures, one set of which is shown at 26 and 27. The cup 22, like the cup 20 is reinforced and padded in a conventional manner.

A prosthetic pad is identified at P. It is removably positioned in the cup 22 and held therein when the postures 26-27 are closed. The pad P comprises a cone shaped body 28 of foam rubber presenting an inner recess 29 the lower portion of which receives added weight in the form of birdseed 30. A fabric casing 31 encloses the body and weight and holds the latter within the recess 29.

A shoulder strap 32 has one end permanently anchored to the front portion 11 as indicated at 33. Likewise, a second shoulder strap 34 has one end anchored to the front portion 10 as shown at 35. Prior to fitting to a particular patient the other ends of the shoulder strap 32 and 34 are free of the band as depicted in FIGURE 5. After fitting they are secured to the back 14 by removable stitching shown at 36 and 37 in FIGURE 6.

To achieve an accurate and comfortable fit of the band B about the torso of a particular patient a pleat or fold such as shown at 38 is formed, this pleat is secured by removable stitching 39. Obviously the size of this pleat may be varied from time to time by first removing the stitching 39, making the adjustment, and then restitching.

While the manner of using the brassiere of this invention during a period of convalescence is believed to be obvious from the illustration of the drawing and description of parts given, it may be briefly outlined by noting that immediately subsequent to the operation the band B and shoulder straps 32 and 34 are adjusted to accurately accommodate any dressing, bandages or binders which may have been applied to the patient. This is achieved without generating any localized pressures over the sore and tender area. Just enough pressure is created to hold the garment in position and there are no buckles, clasps or similar metallic devices which might "bite" into the

patient under pressure and cause discomfort. Moreover, the pressure is applied in areas remote from the incision.

There may be some drawing from the operation incision but this is taken care of by the absorbent properties of the pad P and the fact that the band B is washable. It is also evident that the fasteners 17-18 being located at the front, are readily accessible to the wearer. Thus, she may at any time remove the brassiere and alter either the pleat 38 or the length of the shoulder strap.

The fact that the pad P carries added weight in the form of birdseed 30 complete with the adequate support for the muscles remaining after the operation provided by the wide comfortably fitted band B, enables the patient to assume a normal posture, without hunching, and with the positive assurance she presents an attractive appearance. At the same time the muscles begin to react automatically because of the weight and ultimately acquire the strength necessary to support the shoulder.

While a preferred specific embodiment of the invention is hereinbefore set forth it is to be clearly understood that the invention is not to be limited to the exact constructions illustrated and described because various modifications of these details may be provided in putting the invention into practice within the purview of the appended claims.

The embodiments of the invention in which an exclusive property or privilege is claimed are defined as follows:

1. For use in a past mastectomy convalescent period, 30 a brassiere comprising: a torso encircling band at least seven inches in width and of a non elastic, non stretchable, woven fabric and including front end portions, side portions, and a back all integrally formed as a one piece unit; a breast cup having a lower part permanently secured to the outer surface of one of said front portions; means for detachably securing the upper half of said cup to said front portion; a prosthetic cup removably positioned in said breast cup and including added weight; a device for detachably securing said front portions together at their end edges; a pair of shoulder straps of non-elastic, nonstretchable woven fabric, each of said shoulder straps having one end permanently anchored to one of said front portions at the upper edge thereof and having a free end portion secured to said back by removable stitching; and a pleat formed in said back and held therein by removable stitching whereby said band and shoulder strap may be accurately and comfortably fitted to a patient who may, from time to time, remove the brassiere from her person by opening said detachable device and 50 make such adjustments in said pleat and shoulder strap length as may be necessary for comfort.

2. The convalescent brassiere of claim 1 in which the band is washable and the prosthetic cup has absorbent properties.

3. The convalescent brassiere of claim 1 in which the remaining front portion is cut-away to provide an opening and has mounted thereon over said opening, a breast cup for receiving a healthy breast.
